US00D458023S

(12) **United States Design Patent** (10) Patent No.: **US D458,023 S**
Dzwill et al. (45) Date of Patent: ** Jun. 4, 2002

(54) **CONTACT LENS CONTAINER**

(75) Inventors: **Edward A. Dzwill**, Ponte Vedra Beach; **Scott Frederick Ansell**, Jacksonville, both of FL (US); **Adrianus Hendrik Kooiman**, Waardenburg (NL); **Menno Ben Kubbinga**, Jacksonville, FL (US); **Jan Albert Maria Windey**, Lommel (BE); **Michael W. Litwin**; **Jeffrey H. Roffman**, both of Jacksonville, FL (US); **Jongliang Wu**, Taipei (TW)

(73) Assignee: **Johnson & Johnson Vision Care, Inc.**, Jacksonville, FL (US)

(**) Term: **14 Years**

(21) Appl. No.: **29/113,919**

(22) Filed: **Nov. 12, 1999**

(Under 37 CFR 1.47)

(57) **CLAIM**

We claim the ornamental design for a contact lens container, as shown and described.

DESCRIPTION

FIG. 1 is a perspective view of a contact lens container showing our new design;

FIG. 2 is a right side elevational view thereof, the left side elevation being a mirror image;

FIG. 3 is a top plan view thereof;

FIG. 4 is a front elevational view thereof;

FIG. 5 is a rear elevational view thereof; and,

FIG. 6 is a bottom plan view thereof.
